 corporation of Iowa

Application August 11, 1945, Serial No. 610,236

11 Claims. (Cl. 68—263)

1

This invention is applicable to a wringer for domestic washing machines, and is more specifically directed to manual wringer release and reset mechanism; therefor, such mechanisms all comprising imperative equipment in wringer structures for the protection of the user.

One of the main objects of the present invention is to provide a wringer structure that incorporates a pivotally supported and upstanding frame within the confines of the wringer providing a part of a manual release means that is compactly housed within the wringer frame structure and which eliminates the use of overhead mechanism and such framework that would definitely increase the total vertical height of the wringer. By having an extremely low height wringer the efficiency thereof is enhanced inasmuch as a housewife can then more easily operate the same with a minimum amount of reaching over the top of the wringer for manipulating the clothes.

Another object of the present invention is to construct the wringer as above but with an upper wringer roll which is adapted for rotation upon the axis of a fixed shaft while providing a lower bodily movable roll connected and guided for parallel movement away from the upper roll upon release of the manual wringer release mechanism. The foregoing is made possible by the unique construction of the manual release mechanism and its connections beneath the wringer frame to provide duplicate mechanisms to produce a parallel movement of the lower roll away from the upper roll at the time of release.

Another object of the present invention is to provide a parallelogram framework having manual release bars connected and operable at opposite sides of the wringer with such bars so positioned as to flank the upper wringer roll and to normally prevent engagement of the operator's hands with the upper roll which is entirely exposed in this wringer construction.

Another object of the present invention is to provide manual reset means to produce the required tension through suitable springs for normally positioning and resiliently urging of the lower roll upwardly into operative contact with the upper roll of the wringer for creating the necessary squeezing action to wring the water from the clothes while operating the wringer. This reset mechanism is connectible with the release framework to restore the same into active release position as established by stabilizing means for said framework.

All other objects, and advantages, embodied in the wringer of the present construction will here-

2

inafter be referred to in the following detailed description having reference to the drawings disclosing a preferred embodiment of the wringer of this invention.

5. In the drawings:

Fig. 1 is a side elevational view of a preferred construction of wringer embodying the principles involved in the present invention;

10 Fig. 2 is an enlarged side elevational view of the wringer illustrated in Fig. 1 with parts thereof broken away to more clearly show certain details of construction;

15 Fig. 3 is a transverse cross sectional view of the wringer as taken substantially along the lines 3—3 in Fig. 2 and looking in the direction indicated by the arrows;

20 Fig. 3A is a fragmentary sectional view showing the structure in the lower left part of Fig. 3 in pressure released position;

25 Fig. 4 is an enlarged plan view of the main elements and mechanisms incorporated and combined to provide the manual wringer release and reset mechanism, such view looking downwardly upon the mechanism mentioned from below the upper wringer roll; and

Fig. 5 is a bottom detailed view of the hand operated means employed for resetting the manual wringer release mechanism after the same has been operated.

30 Referring now to Figs. 1 and 2, the main wringer frame construction comprises the housings 1 and 2 rigidly connected by the drain board structure 3 flanking the sides of the lower portion of the wringer as best shown in Fig. 1. The

35 upper wringer roll 4 is mounted for rotation upon a non-rotatable shaft 5, the ends of such shaft being carried on pins 6 and 7 shown in Fig. 2. Pin 6 is supported from a suitable bracket 8 connected with the wringer housing 2 while the pin

40 7 is supported by means of the ears 9 projecting upwardly from the gear casing 10 which houses the usual operating mechanism for driving the wringer rolls in either direction and to interrupt the drive thereto. Such mechanism is conventional in the wringer art and therefore has not been illustrated in any detail. The usual wringer drive shaft 11 of the wringer column extends into the gear casing 10 and connects through conventional gear means to the driving gear 12 connected

45 to drive gear 13 conveniently secured to the roll sleeve 14 to rotate the roll 4 on suitable bushings or bearings 15 and 16 carried upon the non-rotatable shaft 5.

50 The lower roll 17 of this wringer is preferably of smaller diameter than the upper roll 4 to ob-

55

tain a wringing combination wherein the large roll provides a greater squeezing area of contact in combination with a smaller roll better adapted for handling buttons, etc., or small gathered or folded portions of the clothing as the same are passed through the wringer. Furthermore, the use of a smaller lower roll in a wringer of the particular description herein disclosed provides a greater clearance factor permitting greater movement of the lower roll which can be accomplished without increasing the overall height of the wringer structure itself.

This lower roll 17 is carried upon the usual shaft 18 and the latter projects from the opposite ends of the roll and seats within the saddle bearings 19 and 20 as best seen in Figs. 3 and 4. Bearings 19 and 20 are secured by means of pins 21 and 22 respectively to the guide yokes 23 and 24 while the latter are slideably carried within the vertical channels 25 and 26 secured in any convenient manner to the wringer frame.

The spring tensioned link mechanisms 27 and 28 are connected with the bearing units 19 and 20 respectively to normally urge the lower roll 17 into operative pressing contact with the upper roll 4 under normal conditions of operation of the wringer. These mechanisms 27 and 28 are substantial duplicates and function in the same capacity at each end of the wringer. For this reason the explanation will be directed to the link mechanism 27 best illustrated in Figs. 3 and 4. The guide yoke 23 for the bearing 19 is provided with pairs of ears 29 and 30 oppositely related at the upper portion of the slideable bearing structure. Bell cranks 31 and 32 are connected with the ears 29 and 30 by means of the pivot pins 33 and 34 respectively, and such bell cranks 31 and 32 are further pivotally supported upon the pins 35 and 36 carried by the swingable links 37 and 38 that are pivotally supported at 39 and 40 respectively from suitable bearing brackets 41 and 42 connected with the main housing of the wringer. Thus, the pivotal connections 35 and 36 produce roving pivotal points for the bell cranks 31 and 32 to permit fulcruming of the latter links about these pivot points while the pivot pins 33 and 34 of the guide yoke 23 can be vertically moved in a straight line to shift the roll 17 in a vertical path by means of the shaft 18.

A pair of links 43 and 44 are pivotally connected by means of the pins 45 and 46 respectively to the opposite ends of a common link 47, and the latter is pivotally connected at 48 to a bracket 49 suitably connected with the bearing guide channel 25. Links 43 and 44 have their free ends pivotally connected by means of the pins 50 and 51 to the ends of the bell crank levers 31 and 32.

Any suitable spring or tensioning means may be interposed into the link mechanism described and between the latter and a release means to entirely relieve the spring of any tension and at the same time relieve any tension that may be transferred through the link mechanism to the lower roll 17 of the wringer. In the present construction a spring 52 has one end thereof connected with a lug 53 forming an integral portion of the link 43, while the other end of the spring 52 is looped about a pin 54 carried by the semi-circular link 55. This link 55 is pivotally connected at 56 to an arm 57 forming an integral portion of the spring release shaft 58 extending substantially the length of the wringer structure and supported in bearings 59 and 60 connected with the main wringer housing as illustrated in Fig. 1.

With this spring structure it is evident that the tension of the spring is transmitted through the link 43 to the common link 47 pivoted at 48 and from the common link 47 to the link 44 tending to produce clockwise rotation of the link 47 thereby causing links 43 and 44 to urge the pivotal points 50 and 51 inwardly toward the longitudinal vertical median plane of the wringer rolls. This action urges the bell cranks 31 and 32 in a direction for counter-clockwise and clockwise rotation respectively causing the pivotal connections 33 and 34 to be urged upwardly, the link mechanism functioning substantially in the manner of lazy tongs. From this action the guide yoke 23 holds the bearing 19 upwardly under the spring tension thereby holding the lower roll 17 in operative wringing contact with the upper roll 4. Furthermore, as long as the shaft 58 and the connected link 55 are maintained in the particular position illustrated in Fig. 3, the spring 52 is in stretched condition producing the proper tension that is transmitted through the link mechanism to the lower roll in the manner explained.

Since the same description will apply to the corresponding link mechanism 28 incorporated in the outer end of the wringer structure, no further explanation will be tendered excepting to say that the wringer mechanism 28 has been given the same reference characters with *a* attached such as 33*a*, 34*a*, 35*a*, for example, to indicate like parts.

A manual release mechanism including cooperative latch mechanism coacting with the release shaft 58 has been introduced to provide a trigger release means for instantly relieving the tension of the springs 52 and 52*a* to permit the lower wringer roll 17 to part freely from operative contact with the upper wringer roll 4. The manual release mechanism herein employed is best illustrated in Figs. 2 and 3 and comprises a parallelogram framework. This framework comprises two longitudinally disposed shafts or operating rods 61 and 62 pivoted on extensions 63 and 64 forming a portion of the channels 24 and 25 for guiding the lower roll bearings 19 and 20. Connected with the pivotally supported rods 61 and 62 are the U-shaped release bars 65 and 66 having vertical legs 67 and 68 supporting release bars 69 and 70 arranged to flank the opposite sides of the upper wringer roll 4 and to extend longitudinally and beyond the ends of such upper wringer roll. The vertical legs 67 and 68 are disposed in parallel positions and are connected by links 71 and 72 having pivot pins 73 and 74 respectively located to form a parallelogram when considered with the axial positions of the rockable rods 61 and 62.

This entire vertical framework, including the longitudinally carried release bars 69 and 70 is normally maintained in the vertical position illustrated in Fig. 3 by means of the stabilizing unit 75. This positioning means 75 comprises a rod 76 having a flat surfaced head 77 which bears directly against a corresponding flat surface on a block 78 and the latter is secured to the rod 61 in any desirable manner. The rod 76 extends through an opening 79 in any suitable supporting member which in the present construction comprises a non-rotatable supporting shaft 80 mounted on the wringer housing. A spring 81 is interposed between the head 77 of the rod 76 and the supporting shaft 80 to continually urge the two flat coacting surfaces of the head 77 and the block 78 into contact. Therefore, so long as these surfaces are in direct contact illustrated in Fig. 3

the normal positioning of the parallelogram frame and the release bars carried thereby will be held in the predetermined position shown in Fig. 3. However, it is possible to move either one of the release bars 69 or 70 toward or away from the wringer roll 4 against the action of the spring positioning means 75. Any displacement of the shiftable frame will be overcome by means of the stabilizing unit 75 to restore the framework to initial vertical position.

The latch mechanism which is interposed between the parallelogram frame structure and the rock shaft structure is best illustrated in Figs. 3, 3A and 4. This comprises an arm 82 directly connected with the operating rod 62 and a second arm 83 directly secured to the shaft 58; these arms 82 and 83 being provided at their ends with lugs or fingers 84 and 85 respectively, having cooperative flat contact faces 84a and 85a which abut one another when the arms 82 and 83 are held or disposed in the position indicated in Figs. 3 and 4. By this arrangement shaft 58 is held against rotation and the tension induced in springs 52 and 52a is maintained to provide the necessary upwardly exerted pressure for maintaining the wringer roll 17 in operative wringing contact with the wringer roll 4. However, in the event that either one of the release-bars 69 or 70 are moved in either direction toward or away from the upper wringer roll 4, the arm 82 will be shifted about the axial center of the operating rod 62 causing a displacement between the lugs or fingers 84 and 85 and the flat coating contact faces 84a and 85a thereon, thereby permitting the shaft 58 to rock in clockwise direction as viewed in Fig. 3, also swinging the arm 57 about the pivotal center of the shaft to the position seen in Fig. 3A and the inherent tension of the spring reacting between the pivotal centers 56 and the point of attachment of the spring on the lug 53 is of course diminished. This action renders the springs 52 and 52a inoperative to such an extent as to permit adequate movement of the wringer roll 17 away from the wringer roll 4 in the event of an accidental insertion of the hand or other object between the wringer rolls.

It should be noted in this connection that the force line between the extreme spring connected points at 56 and at the lug 53 passes slightly above the axial center of the shaft 58 and such force line is indicated by the dash and dot line in Fig. 3. This force line is designated by the reference character 86 and it is noted by inspection that the same is offset with respect to the axial center of the shaft 58 to prevent a dead center locking condition that would prevent the release of the spring tension upon the displacement of the lugs or fingers 84 and 85 as previously explained.

Various resetting means may be employed for restoring the parts into latched position for re-establishing the spring tension upon the lower roll after manual release bar action. The present construction contemplates the use of a relatively long handle of a type illustrated in Figs. 1 and 5 which is normally disposed underneath the wringer structure. This reset mechanism is generally indicated by 87 and includes the handle 88 pivotally carried upon a vertical stub shaft 89 for rotation about the axis of the latter. The shaft 89 carries a gear 90 which meshes with a complementary gear 91 secured to the shaft 58. Also secured to shaft 89 is a disc 92 provided with peripheral ratchet teeth 93 that are adapted to be engaged by the end of the latch rod or bar 94. Such a bar 94 is provided with complementary

ratchet teeth 95 at the end thereof for direct engagement with the ratchet teeth 93 on the disc 92. The other end of bar 94 carries a roller 96 which cooperates with the cam surface 97 of a suitable hand grip 98 pivotally connected with the handle 88 at the pivot point 99. A spring 100 normally urges the bar 94 in the direction of the arrow 101 to keep the roller 96 up against the cam surface 97 of the hand grip 98. Furthermore, the spring 100 therefore maintains the teeth 95 out of operative engagement with the teeth 93 of the disc 92 under normal conditions of operation. It should also be noted that the spring 100 will tend to hold the hand grip 98 in the full line position shown through the action of the roller 96 as the latter is urged into the cavity 102 of the cam surface 97.

Normally when the handle 88 and its associated parts are not in use the same may be swung towards the wringer about its pivot until the clip 103 engages the holding pin 104 secured to the underside of the wringer frame. This will hold the entire handle structure out of the way beneath the wringer and in a position where the handle 88 will not interfere with the washing operation. However, whenever the release mechanism has been operated and the latch lugs 84 and 85 are disconnected as previously described, the entire mechanism can be easily reset by means of the handle structure illustrated in Fig. 5. The operator merely takes hold of the hand grip 98 to rotate the same away from the wringer upon the roller 96 forcing the bar 94 to slide through guides 105 and 106 toward the disc 92 to engage the teeth 95 with the teeth 93. Upon engagement of the teeth, rotation of the hand grip 98 per se is halted inasmuch as the same will then occupy the dotted line position illustrated in Fig. 5, causing the clip 103 to pull away from the holding pin 104 and rotating the disc 92 to rotate the shaft 89. This will cause proper rotation of the gears 90 and 91 to rotate the shaft 58 until the latch lugs 84 and 85 will again be brought from the released position of Fig. 3A into the latched position of Fig. 3. It should be noted that the lugs or fingers 84 and 85 are provided with oppositely disposed triangular and rearwardly disposed ridges 107 and 108, respectively, to permit the lug 85 to bypass the lug 84 as the shaft 58 is rotated in counterclockwise direction when viewed in Fig. 3. Obviously, this will cause the arm 82 to swing to one side or the other side as the fingers 84 and 85 bypass each other depending upon which way the ridges 107 and 108 happen to meet. Movement of the arm 82 will rock the parallelogram frame to move the release bars 69 and 70 until the lugs 84 and 85 have cleared one another. Thereafter the entire parallelogram frame structure will swing back to its upright position indicated in Fig. 3 through the spring stabilizing mechanism 75 thereby providing a visual indication to the user that the latches are positioned and properly engaged. The hand grip 98 may then be released causing separation of the teeth 95 from the teeth 93 on the disc 92 whereupon the entire unit will again be spring tensioned with the lower roll 17 in operative contact with the upper roll 4. Hand grip 98 together with its handle 88 can then be returned to their normal inoperative stored position as determined by the clip 103 as the same engages with the holding pin 104.

It is to be understood of course that the handle will occupy this position at all times including the periods when the release mechanism is operated

and all of the members disengaged to relieve the spring tension on the lower roll in the manner described. The handle 88 and its attached hand grip 98 and the other mechanism connected therewith remain entirely inactive during the release of the wringer structure. Furthermore, the handle mechanism can be of considerable length to gain an efficient mechanical advantage whereby it is easily within the housewife's power without any great physical exertion to reset the spring tensioning means of the wringer after release thereof by the safety release mechanism.

By the use of the gears 90 and 91 it is possible to provide a handle reset means that may be of fair size inasmuch as the same can be stored in inactive position beneath the wringer. The result is that such a handle is hand operated to move in a horizontal plane disposed beneath the wringer structure. As described, the handle is free under normal conditions but connectible to reset the spring tensioning means of the wringer.

It is to be understood that other equivalent structures may be substituted for those specifically described to perform the particular functions of the mechanisms embodied in the wringer of the present invention. All changes and modifications together with substitutions shall be governed by the breadth and scope of the claims directed to the preferred embodiment of the wringer as herein disclosed.

What I claim is:

1. A wringer having, in combination, separable wringer rolls, link mechanisms including tensioning means connected with one of said rolls to normally urge the same into operative squeezing contact with the other of said rolls, a rock shaft extending between and connecting said link mechanisms for simultaneous operation, manual roll release means connected with said link mechanisms to maintain the rolls in such operative contact, said manual release means comprising a parallelogram framework having portions thereof flanking the wringer rolls, said parallelogram framework having at least one rock shaft disposed adjacent to the aforesaid rock shaft, means to normally hold said framework in predetermined position with respect to said rolls, and latch means connected with and extending between said rock shafts and adapted to counteract the release of said tensioning means of said link mechanisms but releasable upon movement of the parallelogram framework and the second mentioned rock shaft to thereby cause separation of the wringer rolls through said link mechanisms.

2. A roll release mechanism for a wringer having separable rolls and operative tensioning means to squeeze one of said rolls into contact with the other of said rolls, said tensioning means comprising a rock shaft, link mechanism connected between said rock shaft and said one roll, and a spring connected with certain parts of said link mechanism to hold said one roll in operative pressing position, and releasable latch means for holding said rock shaft in a predetermined angular position to produce a given tension in said spring, said releasable latch means comprising pivotal members, a framework movably supported by said pivotal members, means connected with one of said pivotal members to position said framework relative to said wringer rolls, and cooperative latch members carried by one of said pivotal members of said framework and said rock shaft respectively whereby movement of said framework releases said latch members to cause

10 the rock shaft to collapse said spring and to separate the rolls through said link mechanism.

3. A roll release mechanism for a wringer having separable rolls and operative tensioning means to squeeze one of said rolls into contact with the other of said rolls, said tensioning means comprising a rock shaft, link mechanism connected between said rock shaft and said one roll, and a spring connected with certain parts of said link mechanism to hold said one roll in operative pressing position, and releasable latch means for holding said rock shaft in a predetermined angular position to produce a given tension in said spring, said releasable latch means comprising pivotal members, a framework movably supported by said pivotal members, means connected with one of said pivotal members to position said framework relative to said wringer rolls, and cooperative latch members carried by one of said pivotal members of said framework and said rock shaft respectively whereby movement of said framework releases said latch members to cause the rock shaft to collapse said spring and to separate the rolls through said link mechanism, and manual reset means for connection with said rock shaft to move the same in a direction to re-establish said latch members and to again tension said spring through said link mechanism.

4. A roll release mechanism for a wringer having separable rolls and operative tensioning means to squeeze one of said rolls into contact with the other of said rolls, said tensioning means comprising a rock shaft, link mechanism connected between said rock shaft and said one roll, and a spring connected between certain parts of said link means to hold said one roll in operative pressing position, and releasable latch means for holding said rock shaft in a predetermined angular position to produce a given tension in said spring, said releasable latch means comprising a pivotally supported framework, means to position said framework relative to said wringer rolls, and a latch comprising a swingable arm connected to move with said framework, a second swingable arm connected to move with said rock shaft, and an abutment finger on each of said arms disposed in operative contact with each other movement of said framework acting to displace said abutment fingers whereby the rock shaft moves to collapse said spring and to separate the rolls through said link mechanism, and manual reset means for connection with said rock shaft to swing said second arm to position the abutment finger thereof in operative contact with the abutment finger of said first arm to again tension the spring through said link mechanism.

5. A roll release mechanism for a wringer having separable rolls and operative tensioning means to squeeze one of said rolls into contact with the other of said rolls, said tensioning means comprising a rock shaft, link mechanism connected between said rock shaft and said one roll, and a spring connected between certain parts of said link means to hold said one roll in operative pressing position, and releasable latch means for holding said rock shaft in a predetermined angular position to produce a given tension in said spring, said releasable latch means comprising a pivotally supported framework, means to position said framework relative to said wringer rolls, and a latch comprising a swingable arm connected to move with said framework, a second swingable arm connected to move with said rock shaft, and an abutment finger on each of said arms disposed in operative contact with each

other, movement of said framework acting to displace said abutment fingers whereby the rock shaft moves to collapse said spring and to separate the rolls through said link mechanism, and manual reset means for said rock shaft to return the rock shaft arm with its abutment finger in latching position, said framework positioning means automatically swinging said first arm to place its abutment finger in operative holding contact with the abutment finger of said second arm to again tension the spring through said link mechanism.

6. A roll release mechanism for a wringer having separable rolls and operative tensioning means to squeeze one of said rolls into contact with the other of said rolls, said tensioning means comprising a rock shaft, link mechanism connected between said rock shaft and said one roll, and a spring connected between certain parts of said link means to hold said one roll in operative pressing position, and releasable latch means for holding said rock shaft in a predetermined angular position to produce a given tension in said spring, said releasable latch means comprising a pivotally supported framework, means to position said framework relative to said wringer rolls, and a latch comprising a first swingable arm connected to move with said framework, a second swingable arm connected to move with said rock shaft, and abutment fingers on said arms disposed in operative contact with each other, movement of said framework acting to displace said abutment fingers whereby the rock shaft moves to collapse said spring and to separate the rolls through said link mechanism, and manual reset means for said rock shaft to swing the rock shaft arm with its abutment finger into latching position, said framework positioning means automatically swinging said first arm to place its abutment finger into operative holding contact with the abutment finger of said second arm to again tension the spring through said link mechanism, and said abutment fingers having cooperative cam surfaces thereon to bypass one another during relatching thereof.

7. A roll release mechanism for a wringer having separable rolls and operative tensioning means to squeeze one of said rolls into contact with the other of said rolls, said tensioning means comprising a rock shaft, link mechanism connected between said rock shaft and said one roll, and a spring connected between certain parts of said link means to hold said one roll in operative pressing position, and releasable latch means for holding said rock shaft in a predetermined angular position to produce a given tension in said spring, said releasable latch means comprising a pivotally supported framework, means to position said framework relative to said wringer rolls, and a latch comprising a first arm on said framework, a second arm on said rock shaft, and abutment members on said arms disposed in operative contact with each other, movement of said framework acting to displace said abutment members whereby the rock shaft moves to collapse said spring and to separate the rolls through said link mechanism, and manual reset means for said rock shaft to return the rock shaft arm with its abutment member in latching position, said framework positioning means automatically moving said first arm to place its abutment member in operative holding contact with the abutment member of said second arm to again tension the spring through said link mechanism, and said abutment members having dual

5 and oppositely related cam surfaces thereon to bypass one another during relatching thereof, contact of said cam surfaces acting to move said framework thereby providing visual indicating means to signify relatching of said members.

8. A latch mechanism for tensioning means for wringer rolls comprising a shiftable framework, a rock shaft connected with said tensioning means and adapted to tension the latter, an arm fixedly connected with said framework and having an abutment surface thereon, a second arm fixedly connected with said rock shaft and having an abutment surface thereon for operative contact with the abutment surface of said framework arm, whereby shifting of said framework relatively displaces said abutment surfaces to release said roll tensioning means, and reset means connected to move said rock shaft to again position said abutment surfaces of said arms in operative contact, said reset means comprising a handle swingable in a horizontal plane below said wringer rolls, and gear means to connect said handle with said rock shaft.

9. Pressure sustaining and release mechanism 25 for a wringer having a frame with separable rolls therein carried by bearing means, including a linkage system at each end of the frame and connected to the bearing means for one of said rolls on opposite sides of the roll shaft, a tension 30 spring extending in a direction substantially parallel to the plane of each linkage system and connected between opposed portions of each linkage system remote from the connection to the respective bearing means to cause each linkage 35 system to operate in general on the lazy tong principle to establish pressure between the rolls, latch means to hold the linkage systems in position with the springs under tension, and release means operable to disengage said latch means 40 to contract the springs and collapse the linkage systems.

10. Pressure sustaining mechanism for a 45 wringer having a frame with separable rolls therein, one of which rolls is carried in floating bearing means, a linkage system acting on the bearing means of said one roll and including a pair of pivoted links extending in a direction substantially parallel to the plane of each linkage system and connected to said bearing means 50 on opposite sides of the roll shaft, and a tension spring extending in a direction substantially parallel to the plane of said linkage system and connected to opposed portions of said linkage system remote from the connections to said bearing means to cause said linkage system to operate in general on the lazy tong principle and urge said one roll toward the other.

11. Pressure sustaining mechanism for a 60 wringer having a frame with separable rolls therein, one of which rolls is carried in floating bearing means, a linkage system acting on the bearing means of said one roll and including a pair of pivoted links connected to said bearing means on opposite sides of the roll shaft, and a tension spring extending in a direction substantially parallel to the plane of said linkage system and connected to opposed portions of said linkage system remote from the connections to 65 said bearing means to cause said linkage system to operate in general on the lazy tong principle and urge said one roll toward the other, all pivotal connections between pressure applying links of said system being floating.

NICHOLAS L. ETTEL.
